UNITED STATES PATENT OFFICE.

JAMES H. MCCOOL, OF ELLSWORTH, KANSAS.

ATTACHMENT FOR POOL-TABLES.

1,386,577.

Specification of Letters Patent.

Patented Aug. 2, 1921.

Application filed June 5, 1920. Serial No. 386,795.

To all whom it may concern:

Be it known that I, JAMES H. MCCOOL, a citizen of the United States, residing at Ellsworth, in the county of Ellsworth and State of Kansas, have invented new and useful Improvements in Attachments for Pool-Tables, of which the following is a specification.

The present invention has reference to an 10 attachment for pool or billiard tables.

The object of the invention is to provide a 15 pool or billiard table with permanently fixed troughs or racks which are designed to receive therein the playing balls, after the same have been shot into and removed from the pockets of the table, while means is provided between the racks for permitting the gravitating of the balls through the racks, as well as for receiving said balls 20 when the latter are to be again placed on the table in playing position.

A further object is to produce a pool table 25 attachment in the nature of racks which may be either attached to the end or the side of the table, and which includes opposed downwardly inclined members, the confronting ends of which are spaced and open, but are normally closed by a swinging gate, the latter being in normal closed position by the 30 weight thereof, and which, when swung to open position will permit the balls rolling through the racks and being received by the attendant for arrangement in playing position on the table.

35 A still further object of the invention is the provision on a pool table of oppositely arranged downwardly inclined racks, which are preferably in the nature of spaced wire rods having ring members connected to the 40 ends thereof, the said ring members being supported from the under face of the pool table, and the confronting open ends of the opposed sleeves on the troughs being controlled by a swinging gate which may permit of the delivery of the balls from the 45 troughs into a triangular rack of a special construction that is supported on a bracket or the like directly below the troughs.

The foregoing objects, and others which 50 will appear as the nature of the invention is better understood, may be accomplished by a construction, combination and operative arrangement of parts, such as is illustrated by the drawings.

55 In the drawings:

Figure 1 is a fragmentary perspective

view of a pool table provided with my improvement.

Fig. 2 is a similar view but showing the swinging member or gate between the troughs open and the racking frame in a position to receive the balls.

Fig. 3 is a sectional view approximately on the line 3-3 of Fig. 1.

Fig. 4 is a sectional view approximately on the line 4-4 of Fig. 2.

Fig. 5 is a perspective view of the triangular rack.

Fig. 6 is an approximately central vertical longitudinal sectional view therethrough.

A portion of a pool or billiard table is indicated by the numeral 1 in the drawings. My improved rack is preferably attached to one end of the table, the same being of a length approximately equaling the distance 70 between the legs at the end of the table. The improvement is in the nature of oppositely arranged downwardly inclined superimposed racks which include outer end plates 2, that are preferably in the nature of connected 75 rings, each of which has its upper edge provided with a flange 3 apertured to receive a screw or other securing element that enters the bottom of the table 1. In addition to this other flanges may be provided that receive therethrough securing elements that enter the legs of the table. The inner members of the troughs are in the nature of connected rings 4. The upper rings 4 have 80 upstanding extensions 5 which have a connecting bar 6 that may be secured to the under face of the table. To the bar 6 is 85 hingedly secured a substantially U-shaped gate 10 which when in normal vertical position closes the rings. The body of each of 90 the troughs is made up of oppositely disposed rods 8, which provide the sides of the racks, and a concaved bottom 8'. The rods and concaved base portions are, of course, 95 connected to the ring members that form the ends of the racks. Each rack is thus provided with an open top and each rack is arranged at a downward inclination from its outer to its inner end. Therefore, the 100 balls placed in the racks will gravitate toward the confronting ends of the opposed racks that are normally closed by the swinging gate. The concaved bottom portions 8' of the racks rest on the lower rounded walls provided by the inner peripheries of the 105 connected rings 4, and the opening through the rings is of a size to permit of the balls 110

freely traveling therethrough. The swinging gate 10, when in normal vertical position, contacts with lugs 13 at the points of connection between the ring members that form the inner ends of the troughs, and thus the arms of the gate are disposed centrally of the openings through the said rings.

The cross member between the legs of the table has secured thereto a substantially U-shaped member or bracket 14 on which is designed to rest a triangular rack 15 to receive the balls from the troughs. The rack 15 has one of its sides provided with a longitudinal opening 16 which is in alinement with longitudinal grooves on the inner face of the remaining sides of the rack. These grooves are indicated by the numeral 17. The bottom of the rack comprises a flat V-shaped member 18 that has its outer end formed with a handle 19. The bottom is in the nature of a slide, and when the balls are received in the rack, the same is arranged on the bed of the table, in the usual manner, and the slide is withdrawn from the body to permit of the balls being properly racked on the table.

It is thought that the foregoing description, when taken in connection with the drawings, will fully set forth the construction and advantages of the improvement.

What I claim is:

1. In combination with a pool or billiard table, of oppositely disposed downwardly inclined racks arranged thereon, said racks having their confronting faces spaced from

each other and the said ends open and a pivoted gate normally closing the open confronting ends of the racks.

2. An attachment for pool tables for receiving the playing balls therefor, comprising oppositely opposed downwardly inclined racks, each in the nature of a skeleton frame having an open top, and an open inner end, and the said inner confronting ends of the respective racks being spaced and a gravity influenced gate between the confronting open inner ends of the racks for normally closing the ends of said racks.

3. An attachment for pool tables to receive the playing balls thereof comprising oppositely disposed downwardly inclined superimposed racks, each of the opposed racks having their outer ends elevated, means on the said outer ends securing the racks to the table, connected ring members providing the inner ends of the racks, extensions on the upper ring members, a connecting bar for said extensions which is secured to the table, rods providing the sides of the respective racks connected to the end members thereof, a concaved base between the end members of the racks disposed below the rods, a substantially U-shaped gate pivotally secured to the connecting element at the inner ends of the oppositely disposed racks, gravity influenced and normally retained in position to close the said ends of the said racks.

In testimony whereof I affix my signature.

JAMES H. McCOOL.
